[57] CLAIM

The ornamental design of a telephone, as shown and described.

DESCRIPTION

FIG. 1 is a perspective view of a telephone having a base and a handpiece showing my new design;
FIG. 2 is a top plan view of the base;
FIG. 3 is a front elevational view of the telephone;
FIG. 4 is a left side elevational view thereof;
FIG. 5 is a right side elevational view thereof;
FIG. 6 is a rear elevational view thereof;
FIG. 7 is a bottom view thereof;
FIG. 8 is a top plan view of the handpiece;
FIG. 9 is a bottom view of the handpiece;
FIG. 10 is a right side elevational view of the handpiece, the opposite side being a mirror image of the side illustrated;
FIG. 11 is a rear elevational view of the handpiece; and
FIG. 12 is a front elevational view of the handpiece;
FIG. 13 is a front elevational view with the hand piece removed;
FIG. 14 is a rear elevational view with the hand piece removed; and,
FIG. 15 is a left side elevational view with the hand piece removed.
The telephone base and handset have been shown separately in FIG. 2, FIG. 8, FIG. 9, FIG. 10, FIG. 11, FIG. 12, FIG. 13, FIG. 14 and FIG. 15 for convenience of illustration.
